CLAIM

The ornamental design for a camera bag, as shown and described.

DESCRIPTION

FIG. 1 is a perspective view of a camera bag showing our new design;

FIG. 2 is a front elevational view thereof, the rear being a mirror image;

FIG. 3 is a top plan view thereof;

FIG. 4 is a right side elevational view thereof, the left side being a mirror image; and,

FIG. 5 is a bottom plan view thereof.

The broken lines in the figures represent stitch lines.
